Patented Jan. 6, 1976

238,334

MOLDED PACKAGING TRAY FOR MEAT OR THE LIKE

James E. Gilley, South China, Maine, assignor to
Keyes Fibre Company

Filed Apr. 18, 1974, Ser. No. 462,098

Term of patent 14 years

Int. Cl. D9—03

U.S. Cl. D9—219

Fig. 1.

Fig. 2.

Fig. 3.

Fig. 4.

FIG. 1 is a top plan view of a molded packaging tray for meat or the like showing my new design;

FIG. 2 is a side elevational view;

FIG. 3 is an end elevational view; and

FIG. 4 is a cross-sectional view taken along line 4—4 of FIG. 1.

I claim:

The ornamental design for a molded packaging tray for meat or the like, as shown and described.
